CLAIM

The ornamental design for a display screen with an animated radial menu in a graphical user interface, as shown and described.

DESCRIPTION

FIG. 1 is a first image of a display screen with an animated radial menu in a graphical user interface, showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the animated radial menu in a graphical user interface sequentially transitions the images shown in FIG. 1-7. The process or period in which one image transitions to another image forms no part of the claimed design. The broken line showing of a graphical user interface is included for the purpose of illustrating portions of the article and forms no part of the claimed design; the broken line showing of a watch is included for the purpose of illustrating environmental structure and forms no part of the claimed design.
